FIG. 1

FIG. 2

WITNESS

O. R. Weston

INVENTOR

John Neumann
By *Book. Kibb*
Atty.

UNITED STATES PATENT OFFICE.

JOHN NEUMANN, OF CHICAGO, ILLINOIS.

WOOD STOPPER FOR BOTTLES.

1,247,864.

Specification of Letters Patent. Patented Nov. 27, 1917.

Application filed May 29, 1916. Serial No. 100,711.

To all whom it may concern:

Be it known that I, JOHN NEUMANN, a citizen of the United States, residing at Chicago, in the county of Cook and State 5 of Illinois, have invented certain new and useful Improvements in Wood Stoppers for Bottles, of which the following is a specification.

My invention relates to an improved coated 10 wood stopper for bottles and the method of making the same.

The wood stopper now in almost universal use is provided with a rough unfinished uncoated surface and relies upon its own inherent elasticity to produce a tight seal 15 when forced into the bottle mouth.

Perhaps the greatest disadvantage with the ordinary stopper of this class is that it is exposed to the deteriorating, decaying and 20 contaminating influences of the liquids or substances contained in the bottle and is apt to become discolored or to rot, thereby destroying the seal and injuring the contents of the bottle.

25 The object of my invention is to produce an improved stopper with a coated and protected surface which cannot be discolored or injured by the contents of the bottle and which when forced into a bottle neck will 30 create a tight seal at all points between the stopper surface and the surrounding interior wall of the bottle neck.

These and other objects I attain by coating the stopper with a waxy composition.

35 My invention also relates to the method of coating the stopper surface which consists in providing the wooden stopper with a rough unfinished surface and then dipping the same into a molten bath of wax, the hot 40 liquid wax being partially absorbed into the rough surface of the stopper which swells and checks producing an intimate and close adhesion between the stopper surface and the wax when cooled.

45 The objects and advantages of my invention will be more particularly disclosed in the following description and pointed out in the appended claims, references being had to the accompanying drawings in which an 50 embodiment of my invention is shown.

In the drawings

Figure 1, represents a sectional view cut through a fragment of a bottle with a side view of my improved stopper fitted therein.

55 Fig. 2, is a transverse horizontal section through a bottle neck and stopper taken on line 2—2 Fig. 1.

In referring to the embodiment of my invention shown in the accompanying drawings in detail like numerals designate corresponding parts.

While I have shown my improved stopper fitted into the neck of a conventional form of bottle it should be understood that it may be utilized in various other types of receptacles.

In the two figures of the drawings, 1, designates the bottle neck, 2 the stopper stem, and 3 the head of the stopper.

However, tapering or different forms of 70 stoppers or corks other than headed stoppers may be employed.

In my improved method for making the improved stopper, the surface of the wood 75 is left rough and unfinished, not being polished or smoothed, and it is dipped into a bath of hot molten and liquid wax preferably beeswax.

It is left in this bath a sufficient length of 80 time to permit a certain amount of the wax to penetrate into the rough surface of the stopper and to be absorbed, swelling and checking the surface and producing a corrugated surface 4, as shown in Fig. 2.

The coating 5, formed on the outer surface of the stopper of wax is fairly thick 85 as shown in Fig. 2, and it completely surrounds and covers the stopper stem, presenting an impenetrable surface to the bottle contents and protecting the wooden surface 90 of the stopper against rot or deterioration.

Besides the waxy coating provides a sealing film which as the stopper is forced into the bottle neck forms an air and water tight seal at all points between the opposed surfaces of the wax and the interior of the bottle neck.

The stopper is preferably made of cedar or similar soft wood and is first dipped in cold water containing ten per cent. of salt 100 dissolved therein.

This cold water bath produces a checked and swollen condition of the surface of the wooden stopper and after it is removed from the cold bath, it is dipped in a hot molten 105 solution of beeswax, which easily penetrates into the swollen surface of the wood, forming a practically homogeneous joint between the wood and wax coating.

While I have illustrated and described a 110 preferred adaptation for carrying my invention into effect, the same is capable of a wide range of changes, variations, alterations, and modifications without departing

from the spirit of the invention. I therefore do not wish to be limited to the form herein shown and described, but desire to avail myself of such variations, alterations, 5 modifications and changes as fairly fall within the scope of the appended claims or may be construed to come within the same by involving the doctrine of equivalents.

What I claim as my invention and desire 10 to secure by Letters Patent is:—

1. The method of coating a wooden bottle stopper, which consists in dipping it first in brine and then in hot wax.
2. The method of coating a wooden bottle

stopper, which consists in dipping it first 15 in cold brine and then in hot wax.

3. The method of coating a wooden stopper, which consists in roughening its surface, dipping it in cold brine, and then dipping it in hot wax. 20

4. The method of coating a wooden stopper, which consists in roughening its surface, dipping it in cold brine, then dipping it in hot wax, and subsequently cooling it. 25

In testimony whereof I have affixed my signature.

JOHN NEUMANN.
